UNITED STATES PATENT OFFICE.

JOHN P. COLEMAN, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY-SIGNAL.

1,078,127.

Specification of Letters Patent. Patented Nov. 11, 1913.

Application filed April 17, 1909. Serial No. 490,630.

To all whom it may concern:

Be it known that I, JOHN P. COLEMAN, a citizen of the United States, residing in the borough of Manhattan, city, county, and 5 State of New York, have invented certain new and useful Improvements in Railway-Signals, of which the following is a specification.

My invention relates to railway signals, 10 and particularly to that type of railway signal comprising a semaphore having three positions of indication, an operating mechanism using a liquid as a motive force for moving it, and an electrically operated 15 means for retaining it in certain of its positions to which it is moved by the operating mechanism.

I will describe a railway signal embodying my invention with its application in a 20 signaling system and then point out the novel features thereof in claims.

In the accompanying drawings, Figure 1 is a view partly in diagram to show a railway signaling system including a railway 25 signal embodying my invention, and partly in elevation and vertical section to show the operating mechanism of the railway signal. The parts of the operating mechanism are in the position they assume when the sema- 30 phone is in its danger position of indication.

Figs. 2 and 3 are views like Fig. 1, except that they show the parts of the operating mechanism in the positions they assume when the semaphore is in its caution and 35 safety positions, as well as the changes in the several circuits associated with the apparatus. Figs. 4, 5 and 6 are each detail views of the electrically operated means for holding the semaphore in the position to 40 which it is moved by the operating mechanisms. Fig. 4 shows the position of the parts when the semaphore is in the position shown in Fig. 1, and Figs. 5 and 6 the positions of the parts when the semaphore is 45 in the position shown in Figs. 2 and 3.

Figs. 7 and 8 are also detail views of the electrically operated means for holding the semaphore in the position to which it has been moved. Fig. 9 is a cross-sectional view 50 to show the relative arrangement of some of the parts comprised in the railway signal.

Fig. 10 is a detail view of a pump employed in the operating mechanism. Fig. 11 is a detail view showing a modification.

Similar reference characters designate 55 corresponding parts in all of the figures.

In the drawings (see railway signals of the diagrams) I have shown the operating mechanism as being located at the top of the supporting mast or post instead of at 60 the bottom thereof. I do not, however, wish to be limited to this location of the mechanism, as it may be placed at the bottom of the mast or post equally as well. I have also shown the semaphore as being moved 65 from its horizontal position upwardly to its other two positions of indication. The semaphore may be made to move from its horizontal position downwardly to its other two positions of indication equally as well. 70 These different arrangements are understood by those skilled in the art and involve merely mechanical changes between the operating mechanism and the semaphore, which need not be described herein. 75

A designates a visual signal device here shown as being a semaphore, and comprising as usual a blade a and a counterweight a^1 . The counterweight a^1 is adapted when the semaphore is free to move on its pivot a^2 , 80 to move the blade to a horizontal position, which generally indicates "danger" or stop. The blade a is moved from its horizontal to its inclined and vertical positions by means of a fluid pressure apparatus, and in this 85 invention the signal is held or retained in its inclined or vertical position by an electrically operated means generally known in the art as an "electric slot mechanism." A liquid is used as the motive power, and the 90 necessary pressure for the liquid is obtained by means of a pump which is preferably electrically operated and controlled.

B designates a casing for containing the liquid B^1 and some of the moving parts comprised in the operating mechanism. The liquid may be of any of the special oils which are in general commercial use and which do not congeal at extremely low temperatures. Within the casing, and secured 100 therein, is a suitable form of gear pump B^3 and an electrically operated valve B^5 . The

liquid is drawn in at a port b (see Fig. 10) forced through passages b^1 , b^2 , and under the piston b^4 movable in a cylinder b^5 when the valve B^5 is seated. The valve B^5 when unseated permits the liquid to escape from under the piston b^4 and the passages b^1 , b^2 , through the ports b^6 .

The gear pump B^3 is driven by an electric motor C of any desired type, the operation of which is, preferably, controlled through circuits which are opened and closed by the armatures of relays and a circuit controller included in the signaling circuit as will hereinafter appear. The valve B^5 is operated by means of an electromagnet B^{10} which comprises a coil (not shown) an armature B^{11} and a stem B^{12} connected with the armature and valve. This may be of a construction well known in the electrical art. A spring or other device is employed to move the valve B^5 and armature B^{11} in one direction (to unseat the valve) when the electromagnet B^{10} is deenergized. This electromagnet B^{10} is included in multiple circuit with the electric motor C .

The cylinder b^5 is suitably secured within the casing. The stem b^{12} of the piston b^4 is provided with a rack or gear teeth b^7 which mesh with a segment b^8 secured to the pivot a^2 of the semaphore. The gear teeth b^7 are suitably held in mesh with the segment b^8 .

The semaphore in this invention is held in its inclined and vertical position by an electrically operated means generally known in the art as an "electric slot mechanism." Movable with the semaphore are two rollers g , g^1 , which coat with a roller h to retain the semaphore in either its vertical or inclined positions, when the roller h is held against displacement by the weight of the semaphore in returning to its horizontal position of indication. The rollers g , g^1 are mounted in tangentially arranged slots g^4 provided in a pair of disks g^2 , g^3 which are fixed on the pivot a^2 of the semaphore (see Figs. 7, 8 and 9). As the blade is moved from its horizontal to its vertical and inclined positions the rollers g , g^1 in successively traveling over the roller h (when the latter is held against displacement) move upwardly in their tangential slots (see Fig. 7) and after passing the roller h they move downwardly in their slots to one side of the roller h (see Figs. 5 and 6). The trunnions of the rollers g , g^1 which are designated t , the trunnion of the roller h which is designated 2^a , and the pivot 3^a of the lever h^1 in which the roller h is trunnioned, form in effect a toggle, the point 2^a always tending to move downward under the weight of the semaphore acting through the point t , and so long as the point 2^a is held from displacement the blade will be held from a reverse movement. It will be seen in Figs.

5 and 6 that owing to the tangential arrangement of the slots g^4 in which the rollers g and g^1 move, there is no tendency for these rollers to rise in their slots to pass the roller h to permit a movement of the semaphore toward horizontal position. The roller h , at times is held from displacement by the lever h^2 , the links h^3 , h^4 , and armature h^5 provided for the electromagnets h^6 . When the electromagnets h^6 are energized to hold the armature h^5 against movement on its pivot 7^a , the lever h^2 , and links h^3 , h^4 will be held in the positions shown in Figs. 4, 5, 6 and 7 and in this position the pivot 4^a of the lever h^2 , and the connections 5^a , 6^a of the link h^3 with the levers h^1 and h^2 form in effect a toggle, the connection 5^a always tending to move outwardly under the weight of the semaphore transmitted to the roller h to displace it downwardly. The connection 5^a is held against outward movement by the link h^4 and armature h^5 so long as the electromagnets h^6 are energized; but as soon as they are deenergized, the levers and links h^1 , h^2 , h^3 and h^4 and armature h^5 assume the positions shown in Fig. 8 to permit a reverse movement of the blade; that is, in the direction indicated by the arrow. A spring h^8 is designed, after the blade has reached its horizontal position to return the levers and links h^1 , h^2 , h^3 , h^4 and armature h^5 to substantially the position shown in Fig. 7, so that the armature h^5 will be in position to be attracted by the electromagnets h^6 to move and hold these parts in the positions shown in Figs. 4, 5, 6 and 7.

D designates a suitable form of circuit controller having a pair of stationary contacts d , d^1 and movable contacts d^2 , d^3 . The stationary contacts d , d^1 are operated upon the movements of the piston b^4 , and as shown are moved by the insulated end d^4 of one arm of a bell crank lever d^6 , suitably pivoted and carrying a roller d^{14} in the other arm of the bell-crank lever. D^1 designates a second circuit controller, having movable contacts d^6 , d^7 , and a stationary contact d^8 . The movable contacts d^6 , d^7 are operated upon the movements of the piston b^4 and as shown, are moved by the insulated arm d^9 carried by one arm of a bell crank lever d^{10} which is suitably pivoted and carrying a roller d^{11} in the other arm. The two bell crank levers d^6 and d^{10} are connected by a spring d^{12} which tends to move them in one direction of their pivots, while projection d^{13} on the piston stem b^{12} causes movements in a reverse direction.

The operation of the mechanism, without regard to any signaling system, briefly stated is as follows: Assuming the parts to be in the position shown in Fig. 1 and the valve B^5 to be seated, when the circuit on the motor C is closed, the gear pump B^3 is driven to force the liquid B^1 under the pis-

ton to have it move the piston and consequently the blade a to either its inclined position (Fig. 2) or its vertical position (Fig. 3). When the blade a reaches either its inclined or vertical position, the circuit on the motor is opened by the action of the circuit controller D or D^1 and the blade is held in the position to which it has been moved by the electric slot mechanism.

- 10 When the blade is to have a reverse movement under the influence of its counter-weight a^1 , the valve B^s is unseated to allow the liquid to escape through the ports b^s and the magnets h^s are deenergized—the ports b^s may be of any diameter, a liquid dash pot 15 is formed by the liquid, piston and cylinder, and the return movement of the blade is cushioned. The blade may be stopped in its inclined position (in moving from its vertical position) upon the energization of the electromagnets of the electric slot mechanism.

It will be understood, of course, that the piston is properly fitted and packed in the 25 cylinder to insure its proper operation and to prevent undue leakage of the liquid past the piston. The several valves also will be properly fitted and seated to have a minimum leakage. The diameters of the ports 30 and passages will be such as to afford the proper flow and escape of the liquid.

In the drawings, I have shown diagrammatically a portion of a railway which is divided into sections, generally termed block 35 sections, by means of insulated joints x placed in one or both track rails. I have shown one complete section X and portions of two others, Y, Z. At the entrance end of each block section, a railway signal is 40 placed and in the present case where a three position signal is used, it gives an indication of the service condition of not only the section for which it is provided, but also for the section succeeding it. For example, 45 when a train is in the section for which the railway signal is provided (see X, Fig. 1), the blade thereof is in its horizontal position and when the train is wholly in section Y (see Fig. 2) the blade for the section X is in 50 its inclined position, which signifies to a following engine driver that, although the section on which he is about to enter (X), is clear of a train, the succeeding section (Y) is occupied by a train. The railway signal 55 for section X is designated S, and the railway signal for the section Y is designated S^1 , and so on.

Each section is provided with a track circuit which is formed in part by the track 60 rails of the section, a source of current T B at one end of the track circuit, and a relay device R at the other end of the track circuit. The source of current may be alternating or direct and the relay may be of any 65 preferred type best adapted for the railway

to which the signaling system is applied. These parts are conventionally illustrated in the drawings. The function and action of a track circuit with and without a train in the section for which the track circuit is 70 provided is so well understood in the art as not to require further description. In the signaling systems illustrated there is provided a second relay R^1 for each track circuit, the circuit for which is controlled by 75 the armature of the track relay of the next succeeding section. For example, the circuit of the relay R^1 for section X is controlled by the armature of the track relay R provided for the succeeding section Y, 80 which circuit also includes a circuit controller P which is operated upon the movement of the blade of the railway signal. When the blade of the signal is in its horizontal or "danger" position the circuit controller P is opened (see Fig. 1). When the blade is in its inclined or vertical positions, the circuit controller is closed (see Figs. 2 and 3). The circuit for any relay R^1 may be traced as follows: Starting from one pole 90 of a battery Q (which is also used locally to supply current to the motor C, the electrically operated valve comprised in the signal operating mechanism and the electromagnets of the "slot mechanism") it is wire 95 1, relay R^1 , wire 2, circuit controller P, front contact and armature r of the track relay of the next succeeding section, and wire 3 to the other pole of the battery. When this circuit is closed at all points (the armature 100 r and circuit controller P) the relay R^1 is energized to attract its armature r^1 . When open at any point the relay is deenergized and releases its armature r^1 . The armature r^1 , by its movements, closes and opens any 105 circuits in which it may be included.

The operation of the signaling system illustrated in connection with the railway signals, briefly stated, is as follows: With no car or train or any part of it in either of the sections X and Y, but with a train in the section following section Y, the blades of the railway signals, and the condition of the circuits will be in the position shown in Fig. 3. The positions of the parts of the operating mechanism of railway signal S will be those shown in Fig. 3, while the positions of the parts of the operating mechanism of railway signal S^1 will be those 110 shown in Fig. 2. Assume a train W to have 115 entered section X and to have proceeded through the section X and partially into the section Y, as shown in dotted lines in Fig. 1; with this assumption, the blades of the railway signals S and S^1 , together with the 120 parts of the operating mechanisms thereof, will be in the positions shown in Fig. 1, due to the circuits on the coils B^{10} being opened to permit the liquid to escape past the valves B^s and through the ports b^s and opened on 125 130

the electromagnets h^6 , to permit the rollers g^1 and g moving past the roller h (see Fig. 8). The conditions of circuits of the signal system and the local circuits for these two railway signals will be that illustrated in Fig. 1. As soon as the train W entirely leaves section X , the relay R thereof will be energized by its battery and will attract its armature r , to its front contact. Immediately this is done, two circuits will be closed or established, one on the motor C and the other on the coil B^{10} of the electrically operated valve; the circuit for the coil B^{10} may be traced as follows: Starting from one pole 15 of the battery Q it is wire 3, armature r , wires 4, 5, contacts d^1, d^2 of circuit controller D , wire 6, contacts d^8, d^9 of circuit controller D^1 , wires 7, 8, 9—coil B^{10} , and wires 10, 11 to the other pole of the battery. The valve 20 B^5 will then be seated so that the liquid forced by the pump B^3 past the check-valve will lift the piston b^4 . The circuit for the motor C will be that described in connection with the coils B^{10} so far as the wire 8, from 25 which it continues through wire 12, motor C , and wire 13, 11 to the other pole of the battery. The liquid forced by the operation of the pump under the piston, causes the piston to move upward and move the blade a to its 30 inclined position. When the blade reaches its inclined position (see Fig. 2) the bell-crank lever d^{10} is moved on its pivot by the spring d^{12} to cause its end d^9 to break the circuit on the motor C and coil B^{10} by moving the contact d^9 away from contact d^8 , and 35 permit the contact d^9 to move into engagement with the contact d^8 , and thus establish a circuit on the electromagnets h^6 to hold the blade in its inclined position, and thus 40 no more liquid is forced beneath the piston. The circuit established for the electromagnets h^6 may be traced as follows: battery Q , wire 3, armature r , wires 4, 5, contacts d^1, d^2 of circuit controller D , wire 6, contact d^8, d^9 , 45 of circuit controller D^1 ; wire 14, magnets h^6 , and wires 15, 13, and 11 to battery Q . When the car or train W has passed entirely out of section Y (see Fig. 3) its track relay R is again energized and circuits are closed on 50 the motor and coil B^{10} of the operating mechanism of railway signal S^1 in the manner described in connection with railway signal S , so that the blade a of railway signal S^1 will be moved to its inclined position. 55 In so moving, it closes the circuit controller P , and thus the circuit on the relay R^1 for section X is closed and its armature r^1 is attracted (see Fig. 3). When the armature r^1 is attracted, a circuit will be closed on the 60 motor C and coil B^{10} of railway signal S , which may be traced as follows (Fig. 2): Starting from one pole of battery Q , it is wire 3, armature r , wire 4, wire 16, armature r^1 , wire 17, contacts d^1, d^2 of circuit 65 controller D , wires 18, 8, 12, motor C , and

wires 13, 11 back to battery. The circuit for the coil B^{10} is the same as described for the motor C , as far as wire 8, from where it continues through wire 9, coil B^{10} , and wires 10, 11 back to battery; liquid is then forced under the piston to complete its stroke, and move the blade a to its vertical position (see Fig. 3). In moving to this position, the circuits just described for the motor C and coil B^{10} are broken by the bell-crank lever d^6 being moved on its pivot by the lower projection d^{18} , the end d^4 of which bell-crank moves the contact d^8 out of engagement with the contact d^1 (see Fig. 3). The circuit on the electromagnets h^6 is not broken, but is 70 changed by the movement of the bell-crank lever d^5 , becoming as follows: battery Q , wire 3, armature r , wires 4, 16, armature r^1 , wire 17, contacts d^1, d^2 of circuit controller D , wire 6, contacts d^8, d^9 of circuit controller D^1 , wire 14, magnets h^6 , wires 15, 13, 11, to 75 battery Q . The blade a after being moved to its vertical position, is thus held against return movement by the roller h of the slot mechanism as hereinbefore described. 80

Should a car or train back into the section Y the relay R^1 of section X will be deenergized to drop its relay so as to open the circuit on the electromagnets to allow the blade of railway signal S to move to its inclined 95 position in which position the parts and circuits will be that illustrated in Fig. 2. Of course a train entering section X will also open the circuit on the electromagnets h^6 , and armature h^5 will permit the blade of 100 signal S to go to danger (see Fig. 1).

In Fig. 11 I have illustrated a modification of my invention. I dispense with the coil B^{10} and mechanically actuate the valve B^5 through a governor M mounted on the 105 armature shaft of the motor C . A lever m suitably pivoted intermediate its ends is connected at one end with a sleeve M^1 , movable with the governor; the other end of the lever is connected with the stem B^{12} of 110 the valve B^5 . Instead, the lever m may be employed only to seat the valve B^5 and a spring employed to unseat it, in which case the lever m need only engage with the stem B^{12} . The other parts of the operating mechanism of the railway signal will be the same 115 as illustrated in the other figures of the drawing.

In this application I have not claimed various details of my apparatus which may 120 obviously be used in connection with signal devices having other forms of holding mechanism, such, for instance, as the specific means for operating and controlling the signal device; these I have claimed in an 125 application filed by me on March 20, 1909, which bears Serial No. 484,624.

Having thus described my invention, what I claim is:

1. In combination, a pivoted signal de- 130

- vice biased to one position of indication; means for moving it to another position of indication; and a mechanism for holding the signal device in the position to which it has been moved, comprising a roller mounted to move with the signal device and to have movements relatively thereto in a line tangential to a circle described about the pivotal point, an electromagnet, and a movable member controlled by the electromagnet and adapted to engage the roller. 5
2. In combination, a pivoted signal device biased to one position of indication; means for moving it to another position of indication; and a mechanism for holding the signal device in the position to which it has been moved, comprising a roller mounted to move with the signal device and to have movements relatively thereto in a line tangential to a circle described about the pivotal point, an electromagnet, a movable member, and mechanism interposed between the electromagnet and the movable member and controlled by the electromagnet for holding the movable member in engagement with the roller. 10
3. In combination, a signal device biased to one position of indication; means for moving it to another position of indication; and mechanism for holding the signal device in the position to which it has been moved, comprising two parallel oscillating disks movable with the signal device, oppositely arranged slots in said disks, the said 15 slots being tangential to a circle described about the center of oscillation of the disks, a roller mounted in said slots, a movable member adapted to engage with the said roller, and an electromagnet for holding the 20 said movable member in position for engagement with the roller.
4. In combination, a pivoted signal device biased to one position of indication; means for moving it to other positions of indication; and a mechanism for holding the signal device in the positions to which it has been moved, comprising a roller for each position to which the signal device is to be moved, each of said rollers being mounted 25 to move with the signal device and to have movements relatively thereto in lines tangential to a circle described about the pivotal point, a movable member adapted to engage with the rollers, and mechanism including an electromagnet for holding the 30 movable member in position for engagement. 35
5. In combination, a pivoted signal device biased to one position of indication; means for moving it to another position of indication; and a holding mechanism comprising an electromagnet, a movable member, mechanism interposed between the two and controlled by the electromagnet for holding the movable member rigid in one 40 position, a rotatable member moving with 45
- the signal device, a member carried by said rotatable member and mounted for movement relative thereto, the said relative movement being out of and into position for engagement with the first movable member during a movement of the signal device away from its biased position. 50
6. In combination, a signal device biased to one position of indication; means for moving it to another position of indication; and a holding device comprising an oscillating member moving with the signal device, a roller carried by said member and mounted to have movements relatively thereto in a line tangential to a circle described about the center of oscillation, a movable member adapted to engage with the said roller, and mechanism including an electromagnet for holding said movable member in engaging position. 55
7. In combination, a signal device biased to one position of indication; means for moving it to another position of indication; and a holding device comprising a member operatively connected with the signal device and adapted for movement about a central point, a roller carried by said member and mounted to have movements relatively thereto in a line tangential to a circle described about the center of movement of the 60 said member, a second movable member adapted to engage with the said roller, and mechanism including an electromagnet for holding the said second movable member in engaging position. 65
8. In combination, a movable signal device biased to one position of indication, means for moving it to another position; and a holding device for holding it in the last named position comprising an oscillating member operatively connected with the signal device, a second member carried by said oscillating member and mounted thereon to have movement relatively thereto in a line substantially tangential to a circle described about the center of oscillation, a third member, means for holding the third member rigidly in the path of the second member, the tangential movement of the second member permitting it to pass the 70 third member while the signal device is being moved away from the biased position and the third member is held rigidly in the said path, but not permitting it to pass the third member when said third member is 75 held rigidly in its path to allow a return movement of the signal device. 80
9. In combination, a movable signal device biased to one position of indication, means for moving it to another position; and a holding device for holding it in the last-named position comprising a member movable with the signal device, a slot in said member, a roller in the slot, a second member, means for holding the second member 85

rigidly in the path of the roller, the slot being so disposed with respect to the direction of movement of the first-mentioned member that the roller can pass the second member 5 while the signal device is moving away from its biased position and the second member is held rigidly in its path, but that the roller cannot pass the second member to permit a return movement of the signal

device while the second member is held rigidly in its path.

In testimony whereof I have signed my name to this specification in the presence of two subscribed witnesses.

JOHN P. COLEMAN.
